US00D961316S

(12) **United States Design Patent** (10) Patent No.: **US D961,316 S**
(45) Date of Patent: ** *Aug. 23, 2022

(54) **CHAIR**

(71) Applicant: **Steelcase Inc.**, Grand Rapids, MI (US)

(72) Inventors: **Nickolaus William Charles Deever**, E Grand Rapids, MI (US); **Kurt R. Heidmann**, Grand Rapids, MI (US); **Gordon J. Peterson**, Rockford, MI (US); **Mark Spoelhof**, Grand Rapids, MI (US); **James Ludwig**, Grand Rapids, MI (US); **Alyssa Anne Robert**, Kentwood, MI (US)

(73) Assignee: **STEELCASE INC.**, Grand Rapids, MI (US)

(*) Notice: This patent is subject to a terminal disclaimer.

(**) Term: **15 Years**

(21) Appl. No.: **29/814,815**

(22) Filed: **Nov. 9, 2021**

Related U.S. Application Data

(63) Continuation of application No. 29/724,810, filed on Feb. 19, 2020, now Pat. No. Des. 936,984.

CLAIM

The ornamental design for a chair, as shown and described.

DESCRIPTION

FIG. 1 is a front perspective view of a chair; FIG. 2 is a rear perspective view of the chair shown in FIG. 1; FIG. 3 is a right side view of the chair shown in FIG. 1; FIG. 4 is a left side view of the chair shown in FIG. 1; FIG. 5 is front view of the chair shown in FIG. 1; FIG. 6 is a rear view of the chair shown in FIG. 1; FIG. 7 is a top view of the chair shown in FIG. 1; and, FIG. 8 is a bottom view of the chair shown in FIG. 1. The broken lines showing the base and the controls in FIGS. 1-8 are directed to environment and are for illustrative purposes only; the broken lines form no part of the claimed design.
